UNITED STATES PATENT OFFICE.

ROBERT SPEIDEL, OF CALMBACH, WILDBAD, GERMANY.

DEVICE FOR TREATING FOODS.

Original No. 1,502,409, dated July 22, 1924, Serial No. 561,075, filed May 15, 1922. Application for reissue filed June 16, 1926. Serial No. 116,474.

The object of this invention is to provide an apparatus for treating foods, more particularly the extracting of salt from pickled foods or the neutralizing thereof, and also for the washing and cleaning of foods from dirt or other foreign matter.

The complete neutralizing of large quantities of pickled meat, fish and the like has hitherto not been possible, and the processes which have become known up to the present are accompanied by a series of wants and disadvantages which shall be removed by the invention.

Meat, fish and the like which in order to preserve them had been strongly pickled were hitherto best neutralized by placing them into flowing water. In such case the goods were contained in receptacles which gave the water an easy access to the goods and which also allowed the water to quickly flow off again. The water in this case lixiviated the salt contained in the goods. This process had however the disadvantage that also in case of a long action of the water only the outer parts directly affected by the water became to a certain extent neutralized while those parts of the goods placed one on top of the other in the centre and depth, in other words the bulk of them remained unneutralized, as the water was not able to act on these parts. The salt remaining within and near the middle part upon the goods being touched spread again over the neutralized parts so that the total mass practically kept its whole amount of salt. For certain goods, for instance, for such which are used for the manufacture of fish meal it is absolutely essential to remove the amount of salt contained as far as possible without at the same time allowing that losses of nutrition occur. The neutralizing could be achieved by exposing very small quantities to the influence of flowing water. The carrying out of such a process is, however, on the whole not possible in view of the large quantities which have to be handled. In many cases also the kind of the goods to be neutralized forbids the using of such a process. This process has still further the disadvantage that in case of a large content of salt the neutralizing will last from 24 to 48 hours and that already in case of a twenty-four hour treatment the goods in consequence of the lixiviation of albumen lose at least 10% of their nutrition. It has been ascertained

from experiments that when treating large quantities of goods, the nutrition of the goods is considerably decreased in consequence of the treatment with water without the contents of salt being drawn off to the desired extent.

If the water used for the treatment is not of a low temperature, that is to say of about from 5-10 degrees centigrade, but of a higher temperature, the goods perish very easily after a treatment of a long duration.

All these disadvantages are according to the present invention removed by bringing the materials to be neutralized into a receptacle and after having filled the latter with water subjecting the materials to the action of an agitating device, during the agitating fresh water being admitted at the upper end while at the bottom end of the receptacle the salt-containing water is let off.

With the aid of this process it is possible in about from $\frac{3}{4}$ of an hour up to 2 hours to carry through a thorough neutralizing of the goods without an appreciable loss of nutrition occurring. The latter does not quite amount to 1%. The new process makes it possible to use the strongly pickled offals of the fish industry and other pickled raw materials for the manufacture of fish meal. Heretofore the raw materials for the reasons mentioned in the foregoing had to be worked up with a full content of salt, i. e., with about from 5-20%. The fodder obtained therefrom were, however, in consequence of its high contents of salt unsuitable for being fed out alone. They could only be used in very small quantities as an addition to the otherwise used fodder. It must be taken into consideration that for instance a pig can stand 3% of salt in the fodder only for a short period; longer feeding periods with fodder of the content of salt mentioned usually cause the death of the animal.

By means of the new process it is possible to neutralize in the shortest time in one working operation quantities of from 2000-3000 kg. of raw material according to the size of the receiving vessel, the quantity of water admitted and to the amount of power available.

It is often found difficult in washing such foods as spinach and other leafy plants, to thoroughly clean these foods owing to the clustering of the leaves and the irregular

surface presented by them, even where running water is in contact with them, and it is found by the use of my improved device that such foods may be readily washed and thoroughly cleaned in an apparatus of this present invention as the water in the device is caused to whirl about and circulate into all crevices of these goods to thoroughly wash and clean the same, which washing is accomplished in a more thorough manner than is possible by manual manipulation. Owing to the large quantities of food which can be quickly handled in such an apparatus the labor of several persons is eliminated and great saving in expense is obtained.

Further, this apparatus may be used in the refreshing of meats which have become discolored by warm atmosphere, by subjecting to suitable chemical solution in a liquid containing chamber for this purpose.

A further use of this invention is the mixing of many different sorts of products and liquids and as will be readily understood from the construction thereof the operations of this apparatus are accomplished in the shortest possible time and the minimum amount of nutrition is lost by subjecting the food to this treatment.

Upon the accompanying drawings is illustrated one construction of a suitable device for carrying out the process, and it is:

Figure 1 a vertical section along the line A—B of Figure 3,

Figure 2 a side view and

Figure 3 a plan.

The device consists essentially of a vessel α which has preferably the shape of a vertical cylinder. The vessel has journals b on the side with which it is resting in bearings c . The vessel can be swung about the journals b by means of the hand lever d . The lever d is fitted on its lower end with a fork e which is provided with an adjusting screw f . The fork e passes around a collar g affected by the screw f . If with the aid of the hand lever d the vessel α has been swung about its journals b , it can be held in any desired inclined position with the aid of the adjusting screw f and the collar g .

To the bottom of the vessel a bearing h is fixed which receives the bottom journal of a shaft i fitted with agitating wings k . The top end of the shaft i is reduced and it is here gripped by the forked part m of a shaft n having the same axis as the shaft i . A pin o serves to connect the two shafts i and n together. On the upper end of the shaft i and the sieve bottom u are taken out in shaft n is mounted a conical wheel p , which is driven by a conical wheel q fixed to the driving shaft r . The latter is driven by a motor or by a power transmission of any kind.

The driving of the shaft i could of course be effected in another way, for instance by fixing an electric motor to the vessel α which is employed for this purpose.

by means of an intermediate gear drives the shaft i .

Above the vessel α , a water pipe s has been provided for, while at the bottom end a water offlet t has been arranged. Above the water offlet t is a sieve u retaining the goods so that it cannot enter the water pipe. The sieve bottom u is removable. To the water offlet t a siphon pipe v is connected. The siphon pipe may consist for instance of a rubber hose, a flexible metal pipe or of a rigid pipe being extensible and fitted with joints. For carrying the tube v in the present mode of construction, a series of rods have been provided for. These rods enable a raising or lowering of the tube-mouth x . Obviously any other desired adjusting device can be employed for the intended purpose.

It is intended with the arrangement and adjustability of the siphon pipe to be able to adjust at will the height of the column of water effective at the place of outflow. The higher the place of the mouth x is arranged, the less will be the pressure acting at the place of outflow and the smaller will be also the speed of the outflow and the total pressure of the water and of the goods to be handled on the sieve bottom u .

The process is carried out in the following manner:

After the vessel has been brought into the position shown in Figure 1, it is filled with the material to be handled. Water is then admitted by opening the conduit s . As soon as the water has filled the remaining hollow spaces and has risen nearly up to the rim, the shaft i with the agitating wings k is set in motion. The salt containing water flows through the outlet t , the tube v and mouth x . It will be observed that at first a turbid liquid containing a great amount of salt flows off, the liquid gradually becoming clear. Already from the colour of the outflowing water it can be roughly ascertained when the neutralizing has reached the desired degree.

As soon as this stage has been reached, first the agitating device and then the water admission is stopped and the water contained in the vessel is drained away. The pin o is then removed, the vessel α is swung with the aid of the lever d and it is fixed in the desired position by means of the screw f , in order to be able to take the goods out easily.

After the vessel has been emptied, the shaft i and n together. On the upper end of the shaft i and the sieve bottom u are taken out in shaft n is mounted a conical wheel p , which is driven by a conical wheel q fixed to the driving shaft r . The latter is driven by a motor or by a power transmission of any kind.

Further I have shown an operating handle by which the receptacle may be swung down to horizontal position for emptying the same, but any suitable means may be employed for this purpose.

It is understood that although I have enumerated a number of purposes for which the apparatus may be used, I do not wish to be restricted to any of these particular usages as the same may be employed for any purpose for which it is adapted.

The foregoing description is directed solely towards the construction illustrated, but I desire it to be understood that I reserve the privilege of resorting to all the mechanical changes to which the device is susceptible, the invention being defined and limited only by the terms of the appended claims.

I claim as my invention:

1. An apparatus for treating foods consisting of a cylindrical vessel, an agitating device arranged therein, means for supplying fresh water at the top of the vessel, a water outlet in the bottom of the vessel, a sieve above the main bottom of the vessel, means for swinging said vessel about a horizontal axis, and means for driving the agitating device.

2. An apparatus for treating foods consisting of a cylindrical vessel including a bottom, an agitating device arranged in the vessel, and including a shaft, means for admitting fresh water at the top of the vessel, a water outlet at the bottom of the vessel, a sieve above said bottom, and driving means for the agitating device detachably connected to said shaft, standards arranged adjacent the vessel, the vessel having journals supported in bearings in the standards, whereby to permit swinging of the vessel, and means for maintaining the vessel in adjusted swinging positions on said bearings.

3. An apparatus for treating foods consisting of a cylindrical vessel, an agitating device arranged in the vessel, means for supplying fresh water at the top of the vessel, a water outlet in the bottom of the vessel, a removable sieve arranged at a distance from the main bottom of the vessel, said water outlet being arranged beneath the sieve, means whereby to swing said vessel about a horizontal axis, the agitating device including a shaft, means for driving the agitating shaft and having a movable coupling connection with the shaft, including a pin removably insertable between the shaft and an element of said driving means.

4. An apparatus for treating foods consisting of a cylindrical vessel, an agitating device arranged in the vessel, means for admitting fresh water at the top of the vessel, a water outlet in the bottom of the vessel, a removable sieve in the vessel, spaced from the bottom of the latter, means for swinging said vessel about a horizontal axis, a bracket above the vessel, means on the bracket for driving the agitating device and having movable and detachable connection with the agitating device.

5. An apparatus for treating foods con-

sisting of a cylindrical vessel, an agitating device arranged in the vessel, means for admitting fresh water at the top of the vessel, a water outlet in the bottom of the vessel, a removable sieve in the vessel, spaced from the bottom of the latter, means for swinging said vessel about a horizontal axis, a bracket above the vessel, means on the bracket for driving the agitating device and having movable and detachable connection with the agitating device, a flexible siphon pipe having connection with the water outlet, and means for holding said pipe in adjusted positions.

6. An apparatus for treating foods consisting of a supporting means, a vessel mounted on the supporting means for a swinging movement about a horizontal axis, an agitating device in the vessel including a shaft, a driving means for the agitator having an element movably and detachably connected to the shaft of the agitating device, means for supplying water at the top of the vessel, an outlet at the bottom of the vessel, and a siphoning pipe having connection with the water outlet.

7. An apparatus for treating foods consisting of a supporting means, a vessel mounted on the supporting means for a swinging movement about a horizontal axis, an agitating device in the vessel including the shaft, a driving means for the agitator having an element movably and detachably connected to the shaft of the agitating device, means for supplying water at the top of the vessel, an outlet at the bottom of the vessel, a siphoning pipe having connection with the water outlet, means for holding the siphoning pipe in adjusted positions, a device arranged adjacent the vessel to swing the latter, and means for holding the vessel in various adjusted positions on its swinging axis.

8. An apparatus for treating foods consisting of a cylindrical vessel, an agitating device in the vessel, means for operating the agitating device, means for supplying fresh water at the top of the vessel, a water outlet in the bottom of the vessel, a sieve in the vessel above the vessel bottom, means whereby to rotate the vessel about a horizontal axis, and means to hold the vessel in adjusted positions.

9. An apparatus for treating food stuffs and the like which consists of a vessel, bearings having a horizontal axis on which the vessel is mounted to swing, an agitating device arranged in the vessel, a water outlet arranged adjacent the bottom of the vessel, a sieve above the bottom of the vessel, and means for driving said agitating device.

In testimony whereof I have signed my name to this specification.

ROBERT SPEIDEL.
